VENTILATING ATTACHMENT FOR
PRESSING MACHINES

Alfonse G. Maitzen, Park Ridge, Ill.

Application August 9, 1935, Serial No. 35,463

13 Claims. (Cl. 68—9)

Heretofore in pressing machines for garment and laundry purposes, which have press elements between which the articles are pressed, the heating medium supplied to one of the elements causes 5 the temperature in proximity to the machine, and at the places necessary to be occupied by the operator, to be very high, thereby rendering working conditions very disagreeable and uncomfortable.

10 It is one of the objects of the present invention to overcome these difficulties, objections, and inconveniences and to provide an improved attachment for a pressing machine of this character, which will remove the heat from the place which 15 the operator occupies and thereby provide more comfortable working conditions.

The invention consists further in the provision of a hood for the movable press member, which latter is usually the heated member, and which 20 hood is secured to and is movable therewith, the hood being so constructed and arranged as to provide an inlet opening or slot encompassing the edge of the movable press member, and being provided with a discharge outlet, means being 25 associated and carried with the hood for inducing a circulation of the air through the hood and around the pressing members, to be discharged from the hood and directed away from the operator.

30 A further object is to provide an improved attachment of this character which forms a part of the movable press member, so that the pressing machine may be readily shifted and moved into another position to permit re-arrangement 35 of the machine, without interfering with the hood or its associated parts, all of which remain intact.

To the attainment of these ends and the accomplishment of other new and useful objects 40 as will appear, the invention consists in the features of novelty in substantially the construction, combination and arrangement of the several parts hereinafter more fully described and claimed and shown in the accompanying drawing illustrating this invention, and in which

45 Figure 1 is a side elevation of a portion of a pressing machine of this character, having a ventilating attachment connected therewith, constructed in accordance with the principles of this 50 invention.

Figure 2 is a top plan view of the parts shown in Figure 3.

Figure 3 is a sectional view taken on line 3—3, Figure 2.

55 Referring more particularly to the drawing,

the invention is shown in connection with a pressing machine which is diagrammatically illustrated, the numeral 10 designating generally the machine frame having a stationary member 11 supported thereby and a movable pressing member 12 carried by an arm 13 pivotally supported at 14 to an arm or bracket 15 extending from the machine frame. The arm 13 has an operating handle 16 and a counterweight 17 connected thereto and with a counterbalance spring 18.

All of these parts are of the ordinary and well known construction and as before indicated, are merely illustrated diagrammatically to show one form of pressing machine with which this invention can be used.

The invention consists essentially of a hood 19 constructed of any desired or suitable material, preferably of sheet material shaped into the proper form to provide an open side 20 and a reduced portion 21 to form a fan chamber 22 which connects with the inside of the hood, and the fan chamber is provided with a discharge outlet 23.

This hood may be of any desired configuration, but is constructed to be somewhat larger than the movable head or pressing member 12 and is secured in position and supported for movement with the movable head in any desired or suitable manner, such as by means of brackets 24, so that when the movable member 12 is raised and lowered, the hood 19 will be raised and lowered therewith.

The movable member 12 is supplied with a heating medium in the usual manner, such as by means of pipes 25 and the hood 19 is of such a size to provide an open slot 26 around the edge of the movable head or member 12 and the skirt of the hood may, if desired, be of a length that it will extend below the upper surface of the stationary member 11 of the pressing machine.

Within the fan chamber 22 is located a fan 27 which preferably is mounted to rotate about an upright axis 28, the latter being the shaft of a motor 29 which is also arranged within the fan casing or housing 22. This fan and motor preferably constitute a unit and are supported in position in any desired or suitable manner, such as by means of supports or brackets 30 carried by the hood.

50 Within the fan chamber 22 is located a fan 27 which preferably is mounted to rotate about an upright axis 28, the latter being the shaft of a motor 29 which is also arranged within the fan casing or housing 22. This fan and motor preferably constitute a unit and are supported in position in any desired or suitable manner, such as by means of supports or brackets 30 carried by the hood.

55 The fan 27 is preferably arranged adjacent the outlet opening 23 and a screen or reticulated member 31 covers the opening 23 so as to protect the fan.

With this structure it will be manifest that the

hood becomes an integral part of the press and particularly of the movable pressing member or head 12.

The motor is operated in any desired or suitable manner, that is current is supplied thereto by means of the conductors 32 leading from a suitable source of supply of current.

Obviously, the fan chamber 22 may be of any desired configuration and the fan may be propelled by any suitable means, but preferably by means of an electric current and the motor is preferably electric.

In operation and when the parts are in the position shown in Figure 3, the fan 27 rotates in such a direction as to cause a draft of air to enter the slot 26 between the movable head and the lower edge of the hood, preferably encompassing the movable head and a portion of the stationary head when the movable head and hood are lowered, and will be expelled through the discharge opening 23 in the top of the hood or in the fan chamber 22, thus drawing the heat away from the person operating the press and forcing it out through the top of the hood, where it may rise to the ceiling and may be removed or withdrawn by suitable exhaust fans or any other suitable means.

With this construction it will be manifest that the hood will not be in the way of the operator and will be moved upwardly and downwardly or toward and away from the stationary pressing member 11 with the movable head. At the same time the fan will be constantly operating and will draw the heated air into the hood and discharge the same through the outlet opening 23 away from the operator, thereby providing more comfortable working conditions for the operator.

The fan being continuously operated, will also continue to draw away the heated air from the operator even when the movable member and hood are raised.

With this construction it will also be manifest that the motor, fan and hood become an integral part of the machine, the only outside connections being the conduits for conducting the current to the motor, if an electric motor is employed, or the conduits for supplying the necessary power when an hydraulic or other fluid actuated motor is used, and with this construction it will be manifest that the machine can be readily shifted in its position upon the floor so as to permit rearrangement of machines when desired, without the necessity of having to dismantle any couplings or outside connections.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A pressing machine embodying co-operating pressing elements having relative movement one toward and away from the other, the movable one of said elements being heated, an open hood carried with and covering said movable member, said hood having an air discharge outlet, a fan mounted within said hood for causing a circulation of air into the hood, around the press member and through said outlet, and means for operating the fan.

2. A pressing machine embodying co-operating pressing elements having relative movement one toward and away from the other, the movable

one of said elements being heated, an open hood carried with and covering said movable member, said hood having an air discharge outlet, a fan mounted within said hood for causing a circulation of air into the hood, around the press member and through said outlet, and means for operating the fan, the said fan being disposed entirely within and protected by said hood.

3. A pressing machine embodying co-operating pressing elements having relative movement one toward and away from the other, the movable one of said elements being heated, an open hood carried with and covering said movable member, said hood having an air discharge outlet, a fan mounted within said hood for causing a circulation of air into the hood, around the press member and through said outlet, and means for operating the fan, both the said fan and the said operating means therefor being disposed within and protected by said hood.

4. A pressing machine embodying co-operating pressing elements having relative movement, one toward and away from the other, the movable one of said elements being heated, a hood supported by and movable with the said movable element, said hood carried by and covering the last said member, the open side of the hood being spaced from the last said member to form therewith an open slot encompassing the member, there being a discharge outlet for the hood, air circulation creating means within the hood, and means also carried by the hood for rendering the air circulation creating means active, whereby air will be drawn into the hood through said slot and discharged through said outlet away from the operator of the press.

5. A pressing machine embodying co-operating pressing elements having relative movement, one toward and away from the other, the movable one of said elements being heated, a hood supported by and movable with the said movable element, said hood carried by and covering the last said member, the open side of the hood being spaced from the last said member to form therewith an open slot encompassing the member, there being a discharge outlet for the hood, air circulation creating means within the hood, and means also carried by the hood for rendering the air circulation creating means active, whereby air will be drawn into the hood through said slot and discharged through said outlet away from the operator of the press, and a shield for said discharge outlet.

6. A pressing machine embodying co-operating pressing members having relative movement, one toward and away from the other, means for heating the machine, means for drawing the heated air away from the operator of the press, the said means embodying a hood carried by and encompassing the movable press member, said hood having an air inlet and an air discharge outlet, and means carried by the hood and operating to cause air currents to enter the hood and be discharged from the hood through said outlet and away from the operator of the press.

7. A pressing machine embodying co-operating pressing members having relative movement, one toward and away from the other, means for heating the machine, means for drawing the heated air away from the operator of the press, the said means embodying a hood carried by and encompassing the movable press member and forming an air entrance opening encompassing the periphery of the movable member, said hood also having an air discharge outlet, and means carried by

and within the hood and operating to cause air currents to enter the hood through said air entrance openings and be discharged through said air outlet away from the operator of the press.

- 5 8. A pressing machine embodying co-operating pressing members having relative movement, one toward and away from the other, means for heating the machine, means for drawing the heated air away from the operator of the press, the said 10 means embodying a hood carried by and encompassing the movable press member and forming an air entrance opening encompassing the periphery of the movable member, said hood also having an air discharge outlet, and a rotatable 15 fan carried by and within the hood and operating to cause air currents to enter the hood through said air entrance openings and be discharged through said air outlet away from the operator of the press.

- 20 9. A pressing machine embodying co-operating pressing members having relative movement, one toward and away from the other, means for heating the machine, means for drawing the heated air away from the operator of the press, the said 25 means embodying a hood carried by and encompassing the movable press member and forming an air entrance opening encompassing the periphery of the movable member, said hood also having an air discharge outlet, a fan carried by 30 and mounted within said hood, and operating means for the fan also mounted upon and carried by the hood, said fan operating to cause air currents to enter the hood through said air entrance openings and be discharged through said 35 air outlet away from the operator of the press.

10. A pressing machine embodying co-operating pressing members having relative movement, one toward and away from the other, means for heating the machine, means for drawing the heated air away from the operator of the press, the said means embodying a hood carried by and encompassing the movable press member and forming an air entrance opening encompassing the periphery of the movable member, said hood 45 also having an air discharge outlet, a fan carried by and mounted within said hood, and operating means for the fan also mounted upon and carried by the hood, said fan operating to cause air currents to enter the hood through said air entrance openings and be discharged through said

air outlet away from the operator of the press, said fan being rotatable about an axis perpendicular to the pressing surface of said movable member.

11. A pressing machine embodying co-operating pressing members having relative movement one toward and away from the other, a hood covering and mounted to move with the movable press member, the open end of the hood forming with the last said member an air entrance slot encompassing the member, a portion of the hood being shaped to form a fan chamber having communication with the hood and provided with a discharge outlet, a fan in the fan chamber, and means mounted upon the hood for 15 rotating the fan to cause air currents to enter the hood through said slot and to be discharged from said fan chamber out of the hood and away from the operator of the press.

12. A pressing machine embodying co-operating pressing members having relative movement, one toward and away from the other, a hood covering and mounted to move with the movable press member, the open end of the hood forming with the last said member an air entrance 20 slot encompassing the member, a portion of the hood being shaped to form a fan chamber having communication with the hood and provided with a discharge outlet, a fan in the fan chamber, and means mounted upon the hood for rotating the fan to cause air currents to enter the hood through said slot and to be discharged from said fan chamber out of the hood and away from the operator of the press, the said fan 25 rotatable about an axis perpendicular to the 30 pressing surface of said movable member.

13. In combination with a pressing machine embodying co-operating pressing elements having relative movement one toward and away from the other, and means for supplying heat there- 40 to, of a ventilator comprising with said movable member a unitary structure, said ventilator embodying a hood supported by, for movement with and covering said movable member, said hood having a discharge outlet, an air circulation creating means within said hood for causing a circulation of air into the hood around the press member and through said outlet, and means for operating said air circulation creating means.
